TIRE MOUNTING BRACKET FOR VEHICLES

Marvin G. Wertjes, 2118 Valley Park Drive,
Cedar Falls, Iowa 50613

Filed May 31, 1974, Ser. No. 475,209

Term of patent 14 years

Int. Cl. D12—16
U.S. Cl. D12—202

FIG. 1 is a front perspective view of a tire mounting bracket for vehicles showing my new design;

FIG. 2 is a top plan view thereof;

FIG. 3 is a side elevational view thereof as seen from the right of FIG. 2;

FIG. 4 is a front elevational view thereof;

FIG. 5 is a rear elevational view thereof; and

FIG. 6 is a bottom plan view thereof.

I claim:

The ornamental design for a tire mounting bracket for vehicles, as shown.
